(57) **CLAIM**

The ornamental design for a tufting disc, as shown and described.

DESCRIPTION

FIG. 1 is a front, top perspective view of a tufting disc, showing my new design;

FIG. 2 is a front elevation view thereof;

FIG. 3 is a top plan view thereof; and,

FIG. 4 is a bottom plan view thereof.

The curved surface shading of FIGS. 1 & 3 shows a convex-contoured region of the claimed design. The curved surface shading of FIG. 4 shows a concave-contoured region of the claimed design. The broken line in FIG. 4 represents unclaimed environment and forms no part of the claimed design.
